UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

LOCOMOTIVE-STOKER.

1,296,541.

Specification of Letters Patent.

Patented Mar. 4, 1919.

Application filed May 9, 1918. Serial No. 233,453.

To all whom it may concern:

Be it known that I, NATHAN M. LOWER, a citizen of the United States, and resident of Pittsburgh, county of Allegheny, and State 5 of Pennsylvania, have invented certain new and useful Improvements in Locomotive-Stokers, of which the following is a specification, and which are illustrated in the accompanying drawings, forming a part 10 thereof.

The invention relates to stokers for locomotives in which the fuel is transferred from a bin on the tender to the fire-box of the locomotive; and its object is to provide 15 improved means for flexibly connecting the conduit, which leads forwardly from the fuel bin to the locomotive, to the tender in order to permit relative movement of the two vehicles in any direction without placing 20 strain upon the conduit.

The invention consists in a structure in which the conduit is slidably seated on a saddle block which is so supported upon the tender that it may move transversely to the 25 line of draft, such movement being by a sliding movement upon the surface of its support.

Embodiments of both forms of construction are shown in the accompanying drawings, in which—

Figure 1 is a detail longitudinal vertical section of a locomotive and tender, the stoker mechanism being shown in elevation, with some parts broken away;

Fig. 2 is a detail section on the line 2—2 of Fig. 1; and

Fig. 3 is a detail plan view of a portion of the tender showing the carrying device for the stoker conduit.

Only such details of the locomotive, tender and stoking mechanism are shown as are essential to a disclosure of the novel features.

At 10 there is represented a portion of the frame of a locomotive; at 11 the back 45 head of its fire-box, and at 12 the floor of its cab. The floor of the coal bin of the tender is shown at 13, and a portion of the sub-structure of the vehicle at 14.

The conduit 15 for conveying fuel from 50 the tender to the locomotive is shown as located below the floor of the tender, which is apertured over its rear end to permit the passage of fuel. This conduit discharges into a receiving chamber 16, from which the 55 fuel is elevated by any suitable means, there

being shown for this purpose a conduit 17 within which suitable elevating mechanism (not shown) is inclosed, this conduit discharging at its upper end through a nozzle 18 into the fire-box.

The conduit 15 is preferably flexibly united with a casing of the receiving chamber 16, as by a ball and socket joint, represented at 19. The rear end of the conduit rests and may slide in a saddle block 20, 60 the upper face of which is complementary in shape to the configuration of the bottom of the conduit. Preferably the conduit is U-shaped in cross section, as shown in Fig. 2, and the upper face of the saddle block is 65 concave.

The saddle block 20 rests and is free to slide upon the supporting block 21 in any direction, its movements being limited, however, by an upstanding flange 23 secured to 70 the upper face of the block 21 and inclosing but being normally spaced apart from the saddle block.

Lateral movement of the conduit 15, due to the rounding of track curves, or for other 80 reasons, will cause the saddle block to turn upon its seat. Any relative longitudinal movement of the locomotive and tender will cause the conduit to slide longitudinally upon the saddle block, or a part of this 85 movement may be of this block upon its supporting base, depending upon the relative friction developed between the conduit and saddle block 20, or between it and the supporting block 21. By this arrangement 90 the conduit is relieved from some of the wear incident to longitudinal movement.

While a preferred form of construction is shown, the invention is of sufficient scope to include any device in which the conduit is 95 slidably supported in a saddle block capable of movement in a horizontal plane transverse to the line of draft.

I claim as my invention—

1. In combination, a locomotive, a tender, 100 means mounted on the locomotive for delivering fuel into the fire-box thereof, a laterally movable saddle block carried by the tender, and a conduit connected with the delivering means and being mounted and 105 longitudinally movable upon the saddle block.

2. In combination, a locomotive, a tender, means mounted on the locomotive for delivering fuel to the fire-box thereof, a conduit 110

connected with the delivering means and having its bottom transversely curved, a saddle block mounted on the tender and being movable transverse thereto, the upper face of the saddle block being curved complementary to the bottom of the conduit and forming a seat therefor upon which the conduit is longitudinally slideable.

3. In combination, a locomotive, a tender, means mounted on the locomotive for deliv-

ering fuel to the fire-box thereof, a laterally movable saddle block carried by the tender and having its upper face channeled, a conduit connected with the delivering means and being slidably supported within the channel of the saddle block, such channel and the transverse contour of the bottom of the conduit being complementary in form. 15

NATHAN M. LOWER.
